UNITED STATES PATENT OFFICE.

QUINCY BATES YAPLE, OF ARLINGTON, KANSAS.

SOCKET-WRENCH.

1,372,113.

Specification of Letters Patent. Patented Mar. 22, 1921.

Application filed January 3, 1920. Serial No. 349,321.

To all whom it may concern:

Be it known that I, QUINCY B. YAPLE, a citizen of the United States, residing at Arlington, in the county of Reno and State of Kansas, have invented certain new and useful Improvements in Socket-Wrenches, of which the following is a specification.

This invention relates to certain new and useful improvements in socket wrenches and 10 designed primarily for use in tightening, loosening and removing nuts which bind or clamp elements employed in automobile engine constructions, more particularly nuts not accessible to the ordinary type of wrench 15 and for other purposes wherein the wrench is found applicable, and the invention has for its object to provide, in a manner as hereinafter set forth, a wrench which is simple in its construction and arrangement, 20 strong, durable, efficient and convenient in its use and inexpensive to manufacture.

With the foregoing and other objects in view, this invention consists of the novel construction, combination and arrangement 25 of parts as hereinafter set forth and more specifically described and illustrated in the accompanying drawings wherein is shown an embodiment of the invention, but it is to be understood that changes, variations 30 and modifications can be resorted to as come within the scope of the claims hereunto appended.

In the drawing:—

Figure 1 is a vertical section taken through 35 my wrench, and Fig. 2 is a section taken on the line 2—2 of Fig. 1.

Referring to the drawings in detail, the wrench comprises a body portion 1 which is elongated and has a longitudinal bore for 40 receiving the shaft 11. An integral arm 2 extending below and parallel to the body 1 is provided with a sleeve 3 which has a bore extending at right angles to the bore provided in the body 1.

45 A pair of arms 4 extend from the other end of the body 1 at right angles thereto and terminate in the arms 17 which extend parallel to the body 1. The arms 17 terminate in the sleeve 5 and a pocket 6 for receiving 50 the shaft 7 which carries the socket 8.

A beveled gear 9 is fixedly mounted upon the shaft 7 and situated adjacent the lower end of the sleeve 5 and meshes with a beveled gear 10 mounted upon the shaft 11. Upon 55 the other end of the shaft 11 is mounted the beveled gear 12 which meshes with a beveled

gear 13 carried by a shaft 14 extending through the sleeve 3. A bell-crank lever 15 of the usual construction is provided contiguous with the shaft 14 and has the usual 60 handle or knob 16.

From the above description it is clear that by the rotation of the shaft 14 by means of the bell-crank lever 15 that rotary motion will be given to the beveled gear 13 thereby 65 rotating the beveled gear 12 so as to in turn give rotary movement to the shaft 11. This shaft 11 will rotate the beveled gear 10 which is meshed with the beveled gear 9 thereby causing the shaft 7 to rotate for re- 70 volving the socket 8.

Having thus fully described my invention, what I desire to claim and secure by Letters Patent is:—

1. In a device of the class described, the 75 combination of a body provided with a longitudinal bore, a shaft mounted within said body, one end of said body provided with a depending arm terminating in a right angular extension running parallel 80 with said body, a sleeve provided upon said arm, said sleeve extending at right angles to the bore of said body, a pair of arms offset from the other end of said body and extending parallel thereto, one of said arms 85 provided with a sleeve having a bore extending at right angles with the bore in said body and the other arm provided with a pocket, a shaft having beveled gears at each end mounted within the longitudinal bore 90 of said body, a shaft having a socket on one end and a beveled gear adapted to mesh with one of the beveled gears of the shaft extending through the bore of said body, 95 said socket shaft adapted to pass through the sleeve provided in one of the pair of said arms at the end of the last mentioned shaft, swiveled in the pocket provided in the other arm of the said shaft, an operating shaft having a beveled gear adapted to mesh 100 with the beveled gear provided upon the shaft provided in the body portion extending through the sleeve provided in the first mentioned arm, and means provided for operating the last mentioned shaft. 105

2. A device of the class described comprising a body portion, a shaft rotatably extending therethrough and having gears upon each end, a pair of arms extending from said body portion, one of said arms terminating in a sleeve and the other arm terminating in a pocket, a shaft extending through said 110

sleeve and having its end resting in said pocket and said shaft disposed at right angles to the first mentioned shaft, a gear wheel disposed on said second mentioned shaft adapted to mesh with one of the gears on the first mentioned shaft, a third shaft disposed parallel to the second mentioned shaft, a gear on said shaft adapted to mesh with the other gear on the first mentioned

shaft and means provided on the last mentioned shaft for rotating same.

In testimony whereof I affix my signature in presence of two witnesses.

QUINCY BATES YAPLE.
